CLAIM

I claim the ornamental design for a shotgun, as shown and described.

DESCRIPTION

FIG. 1 is a left side isometric view, from above, of the first embodiment of a shotgun according to the invention;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a right side isometric view thereof from below;

FIG. 9 is a left side isometric view, from above, of the second embodiment of a shotgun according to the invention;

FIG. 10 is a top view thereof;

FIG. 11 is a bottom view thereof;

FIG. 12 is a left side view thereof;

FIG. 13 is a right side view thereof;

FIG. 14 is a front view thereof;

FIG. 15 is a rear view thereof; and,

FIG. 16 is a right side isometric view thereof from below.

The broken lines in the figures form no part of the claimed design.
